CLAIM

The ornamental design for a motorized skate board with seat and footrests, as shown and described.

DESCRIPTION

Incorporated herein by reference is our prior co-pending design patent application Ser. No. 29/100,832, filed Sep. 13, 1999.

FIG. 1 is a perspective view of a motorized skateboard with seat and footrests showing our new design;

FIG. 2 is a left side elevational view thereof;

FIG. 3 is a right side elevational view thereof;

FIG. 4 is a front elevational view thereof;

FIG. 5 is a rear elevational view thereof; and,

FIG. 6 is a top plan view thereof.

The bottom is substantially unornamented.

The surfaces or portions of the article not shown in the drawing or described in the specification form no part of the claimed design.
